(57) **CLAIM**

The ornamental design for a portable MP3 music player, as shown and described.

DESCRIPTION

FIG. 1 is a perspective view of a portable MP3 music player showing my new design;

FIG. 2 is an enlarged front elevational view thereof;

FIG. 3 is a right side elevation view thereof, the left side being a mirror image of the right;

FIG. 4 is back elevation view thereof;

FIG. 5 is a top plan view thereof; and,

FIG. 6 is a bottom plan view thereof.

The broken lines in FIG. 1 are for illustrative purposes only, are solely intended to show the environment in which the invention is used, and form no part of the claimed design.
